WINDING REEL

Kenneth Nesbitt, Ottawa, Ontario, Canada

Application August 14, 1945, Serial No. 610,703
In Canada December 30, 1944

8 Claims. (Cl. 242—68)

1

This invention relates to winding reels and more particularly does it relate to reels of this character for winding paper web thereon as it comes from a paper making machine.

In the art of paper making, winding reels are employed for the purpose of winding the paper web thereon as it comes from the calender rolls of the paper making machine without interfering with the continuous run of paper from the machine. It is common practice therefore in winding operations to dispose a winding reel on each side of the winding drum and when a given quantity of paper is wound upon one reel the opposite reel is started, brought up to winding speed and the paper web or sheet then switched from the full to the empty reel without interfering with the continuous paper run.

The starting or rotating operation of the empty reel on the machine side, commonly referred to as the "stack reel," in many instances is carried out by lowering the empty winding reel at such an angle that only one side or end thereof contacts the winding drum and such contact is outside the travel limits of the moving paper web. From this position the reel is lowered with sufficient contact or drag on the drum to induce it to first rotate and then attain a rotative speed corresponding to that at which the drum is rotating. The full length of the reel is then lowered into as nearly a parallel position with the drum as possible and into contact with the paper web passing over the drum.

The operation of contacting one end of the winding reel with one end of the rotating drum for reel starting purposes and then endeavouring to lower the full length of the reel into even contact with the moving paper web frequently "cracks" or "breaks" the edge of the web or sheet and in the event these cracks or breaks are of a dimension sufficiently large to interfere with the width of paper trimmed on a winder, as they frequently are, this run of paper is wasted for from the time the "crack" or "break" occurs in the paper until the new reel reaches winding speed for switching operation, paper continues to run from the machine and such paper run during that interval represents a loss of large quantities of paper to say nothing of the economical phase or the lowering of production.

Among the objects of the invention are to provide a winding reel with yieldable, and initial web-straddling means which may be started and brought up to rotation at the required winding speed before being fully brought into engagement with the web thus avoiding "cracking" or

"breaking" the paper web and the resulting substantial loss of paper, and waste of time and further eliminates the danger of workmen's clothing being entangled therewith.

5 Yet a further object of the present invention is to provide a device of this character which is simple and rugged in form and one that will the more satisfactorily perform the functions required of it.

10 Having regard to the foregoing and other objects and advantages which will become apparent as the description proceeds, the invention consists essentially in the novel combination and arrangement of parts hereinafter described in detail and illustrated in the accompanying drawings in which:

Figure 1 shows an end view of an embodiment of the present invention which for purposes of illustration is shown in operative position on the 20 "dry-end" of a paper machine.

Figure 2 is a plan view of the present invention shown in detached form.

Figure 3 is an enlarged sectional view taken on the line 3—3 of Figure 2, and

25 Figure 4 is a section taken on the line 4—4 of Figure 3.

Referring now to the accompanying drawings disclosing an embodiment of the present invention and wherein like letters and numerals of reference designate corresponding parts in the different illustrations, the letter A indicates the present invention as a whole while the letter B indicates a fragmentary portion of the "dry-end" of a paper making machine.

30 For operative purposes the winding reels A are removably supported in any suitable type of end bearings 15 by arm means 16, the arms 16 being swingably connected to the frame of the paper making machine B as at 17. Suitable and well known mechanism is provided for swinging arms 16 with reels A thereon toward winding drum 18 for purposes of "starting" and then bringing the reel up to proper rotative speed as will be later explained.

45 The winding reel herein disclosed includes a casing or shell 19 of appropriate length and suitable material having end supporting shafts 20 all of which is known in the art.

In accordance with the present invention, each end of the winding reel A is provided with yieldably mounted contact collars or discs 21 which represents a "floating" mounting. These collars or discs, as particularly illustrated in Figures 2 and 3 have an outside diameter in excess of or greater than the outside diameter of the main

body of reel 19 so that when the reel A is lowered into contact with the winding drum 18 for purposes of starting the rotative movement of the reel, the collar members straddle the paper web and contact the drum outside the limits of such paper web. Here it is considered proper to mention that by reason of the annular structure of the disc members, their rounded edges and the fact that they protrude a limited extent beyond the surface of the reel body, eliminates the danger of workmen becoming entangled therewith.

Each of the collar members or discs 21 is constructed with a central bore or opening 22 the diameter of which is greater than the outside diameter of the shafts 20 while a series of concentrically arranged bores or openings 23 are formed between the inner and outer peripheries of the collar members. Within the openings 23 of the collars I mount annular sleeves 24 composed of rubber or like yieldable material while within the core of the members 24 I mount metallic spacer rings or sleeves 25 that are just a little longer than the thickness of the discs 21 and yieldable sleeves 24.

The means for mounting the collar members 21 on the ends of the reel A to effect a floating mounting comprise end plates 26 which are fitted over the shafts 20 at the outside of collars 21 and are connected to the reel A as by countersunk bolts or the like 27. These bolts it is observed extend through the metallic spacer rings, with their necessary margin of length over the thickness of the collars 21, and into the ends of the reel head thereby maintaining the collars in floating relationship to reel A.

With the resilient members 24 disposed between the collar or disc members 21 and bolts 27, the mountings will yield when a pressure is imposed on the outer periphery of the discs or collars however in the absence of a peripheral pressure the discs are maintained in a normal position such as seen in Figures 2 and 3, so that they engage the ends of the rotating drum for reel rotatting purposes without contacting the paper web.

From the foregoing it will be observed that the full length of the reel is lowered parallel with the drum 18 until the disc members contact the drum outside the limits of the moving paper web and the reel is quickly brought up to rotative winding speed. With this accomplished the reel is lowered into tight parallel contact with the moving paper web, the yieldable mountings enabling the disc members to ride the drum in the same plane as the reel body. This precise and accurate lowering of the reel enables it to move into tight, even contact with the moving paper web at a corresponding speed and without "cracking" or "breaking" the paper sheet. Simultaneous with the lowering of the full weight of the reel, air jets are operated to "break" the paper web and turn it on the empty rotating winding reel, without interfering with the continuous run of paper from the paper making machine.

Many changes may be made in the above and many apparently widely different embodiments constructed without departing from the spirit or essential characteristics of the invention. It is intended therefore that the present disclosure be interpreted as illustrative rather than restrictive and that all changes coming within the meaning and range of equivalency of the claims are intended to be embraced therein.

What I claim as my invention is:

1. In a device of the character described, a

body member, disc members mounted on opposite ends of the body member, the diameter of the said disc members exceeding the diameter of the body member, and disc member supporting means including a plate, plate securing means, plate spacing means on said securing means, and yieldable members interposed between the plate spacing means and the disc members, the length of said plate spacing means being greater than the thickness of a disc to floatingly support the said disc members on the body member.

2. For a paper making machine, a winding reel consisting of a reel body, end plates disposed on opposite ends of said body, attaching means fastening said end plates to said body, spacer sleeves between said respective plates and said body through which said attaching means pass, and resiliently mounted members located between said reel body and said spaced end plates normally extending beyond the periphery of said reel body.

3. For a paper making machine, a winding reel consisting of a reel body, end plates disposed on opposite ends of said body, attaching means fastening said end plates to said body, spacer sleeves between said respective plates and said body through which said attaching means pass, and resiliently mounted members of greater diameter than said reel supported by said spacer sleeves and located between said reel body and said end plates.

4. For a paper making machine, a winding reel consisting of a reel body, end plates disposed on opposite ends of said body, a concentrically arranged row of attaching means fastening said end plates to said body, spacer sleeves between said respective plates and said body through which said attaching means pass, and resiliently mounted annular members of greater diameter than said reel located between said reel body and said end plates and having a concentrically arranged row of openings registering with said attaching means and spacer sleeves that pass therethrough, the openings in said annular members being substantially larger than the diameter of said spacer sleeves and said annular members being of less thickness than the length of said spacer sleeves.

5. For a paper making machine, a winding reel consisting of a reel body, end plates disposed on opposite ends of said body, a concentrically arranged row of attaching means fastening said end plates to said body, metallic spacer sleeves between said respective plates and said body through which said attaching means pass, resiliently mounted annular members of greater diameter than said reel located between said reel body and said end plates and having a concentrically arranged row of openings registering with said attaching means and spacer sleeves that pass therethrough, said annular members being of less thickness than the length of said spacer sleeves, and rings of yieldable material in the openings in said annular members surrounding said metallic spacer sleeves.

6. A winding reel for a paper making machine consisting of a reel body, a coaxial stub shaft extending from each end thereof, an end plate with a central, shaft-receiving bore attached to each end of said reel body but spaced therefrom, and a disk member of greater diameter than said reel body and spaced end plate and of less thickness than the spacing of said end plate from said reel body resiliently mounted between said body and each of said end plates, said disk

member having a central bore of greater diameter than said stub shaft.

7. For a paper making machine having a revolving drum and a continuous web of paper issuing from said machine over said revolving drum; 5 a paper winding reel engageable with said web of paper passing over said drum, an annular member on each end of said reel having a greater diameter than said reel and engageable with said drum on either side of said web, said annular members each having a large central bore and a series of concentrically arranged openings between said bore and its outer periphery, a yieldable ring in each of said openings, a metallic sleeve passing through each of said rings, and fastening means attaching said sleeves to said reel.

8. For a paper making machine having a revolving drum and a continuous web of paper issuing from said machine over said revolving drum; 20 a paper winding reel engageable with said web of paper passing over said drum, an annular member on each end of said reel having a greater diameter than said reel and engageable with said drum on either side of said web, said annular 25

members each having a large central bore and a series of concentrically arranged openings between said bore and its outer periphery, a ring of yieldable rubber-like material in each of said openings, a metallic spacer sleeve passing through each of said rings, said sleeves being of greater length than the thickness of said annular members, reel end plates applied over said annular members, and bolts countersunk in said end plates attaching the same to said reel and passing through said metallic spacer sleeves.
